W. W. DOUGLASS.

REFRIGERATOR.

APPLICATION FILED OCT. 20, 1917.

1,288,394.

Patented Dec. 17, 1918.

UNITED STATES PATENT OFFICE.

WILLIAM WOODROW DOUGLASS, OF MIAMI, FLORIDA.

REFRIGERATOR.

1,288,394.

Specification of Letters Patent. Patented Dec. 17, 1918.

Application filed October 20, 1917. Serial No. 197,636.

To all whom it may concern:

Be it known that I, WILLIAM W. DOUGLASS, a citizen of the United States, and a resident of Miami, in the county of Dade 5 and State of Florida, have invented certain new and useful Improvements in Refrigerators; and I do hereby declare the following to be a full, clear, and exact description of the invention, such as will enable others 10 skilled in the art to which it appertains to make and use the same.

This invention relates to improvements in refrigerators of the "evaporative" type,—the object of the invention being to provide 15 a refrigerator of the type specified in which adequate provision shall be provided for supplying water to the fabric walls thereof and maintaining the latter well saturated throughout their full extent 20 and to so construct the refrigerator that it shall be ant proof.

With this and other objects in view the invention consists in certain novel features of construction and combinations of parts 25 as hereinafter set forth and pointed out in the claims.

In the accompanying drawings, Figure 1 is a front elevation of a refrigerator embodying my improvements. Fig. 2 is an 30 end view. Fig. 3 is a view in section, and Figs. 4, 4^a and 5 are detail views.

1 represents the bottom of the refrigerator which may be mounted on suitable legs 2 and supports the superstructure of the 35 refrigerator. This superstructure comprises a plurality of posts 3 to which the framework is secured and a suitable frame 4 is provided for the accommodation of a door 6. A top 7 is secured to the posts 3 and to said 40 framework and supports a tank 8 for water. All of the joints between the wooden parts of the structure are made sufficiently tight to render them "ant" proof. This may be accomplished by mashing the wood of one 45 member of each joint so as to form a groove and then removing the wood from each side of such groove. Then when the two members forming a joint are brought together and subjected to moisture during the ordinary 50 use of the refrigerator, that portion of the wood which has been mashed will expand and press tightly against the adjacent member of the joint and form a water tight and "ant" proof connection.

55 All of the walls of the structure including the panel or panels of the door consist

of fabric material such as canvas or duck as indicated at 9. The upper and lower edges of these canvas walls are securely held in the joints of the framework, which latter are calked by the protruding or swelled portions of the wood as above described and as illustrated at 10.

In the drawing, Fig. 1, I have shown a single door in the front of the refrigerator 65 and to the canvas walls a plurality of pockets or troughs 12 composed of the same material as that of which said walls are composed are secured at their lower edges and each of said pockets or troughs extends 70 from one side of the door around the refrigerator to the other side of the door and the canvas panel of the door is provided with similar pockets 13. The pockets flare outwardly from their lower edges and it 75 may be desirable to provide means for supporting said pockets at their upper edges. For this purpose hooks 14 of non-corrodible metal may be provided.

The walls of the tank 8 are provided close 80 to their bottom edges with outlets 15 with which a plurality of pipes (preferably of the flexible type) 16 communicate. Some of these pipes or tubes may be disposed to discharge into the upper pocket or trough while 85 others of said pipes or tubes are arranged to discharge against the canvas walls intermediate of the pockets or troughs thereon. At the bottom of the refrigerator a trough 17 is provided to receive water flowing from the 90 canvas walls and in order to prevent water from getting inside of the refrigerator at the bottom thereof, I provide a trough 18 which may be made of water proof material and locate said trough inside of the refrigerator and in such position that it will act 95 as a deflector and thereby insure the passage of water to the trough 17. The trough 17 has a tongue-and-groove connection with the bottom of the refrigerator as indicated at 19 100 and such connection is provided with the calking means hereinbefore described. I prefer to make the trough or gutter 17 at the bottom of the refrigerator of wood and a suitable overflow 17^a is provided for this 105 trough or gutter so as to maintain a quantity of water in the latter at all times to prevent ants from entering the refrigerator, the latter being thus made ant-proof.

To control the discharge of water from the 110 tank 8 through the outlets 15 and pipes 16 to the canvas walls and pockets, I provide a

plurality of valves 20 which may conveniently consist of levers pivotally supported between their ends by the walls of the trough 8.

5 The refrigerator will be provided with suitable shelves 21 and these may be conveniently supported by means of suitable brackets 22.

10 Water supplied from the pipes 16 and discharged either into the pockets or troughs 12 or against the canvas walls will be absorbed by the latter and the excess will become deposited in the next lower pocket or trough through which it will pass and by 15 which such water will be fed to the canvas wall, thus keeping the full extent of the canvas composing the walls of the refrigerator thoroughly saturated with water so that air passing through said walls will become saturated with moisture and the evaporation thereof will effect reduction of temperature within the refrigerator, as is well understood. Should any considerable amount of 20 water accumulate in the pockets or troughs 12, this water will be equally distributed by reason of the fact that said pockets or troughs extend around the refrigerator from one side of the door opening to the other.

30 Slight changes might be made in the details of the structure and hence I do not wish to restrict myself to the precise details shown.

Having fully described my invention what I claim as new and desire to secure by Letters-Patent, is:

1. In a refrigerator, the combination with an open framework and absorbent walls, of pockets or troughs of absorbent material pro-

jecting from the absorbent walls, a water supply tank, and means for conveying water 40 from said tank to said absorbent walls.

2. In a refrigerator, the combination of a frame and walls of absorbent material, said frame comprising parts having grooves and parts having tongues entering said grooves, 45 said tongues having portions expansible by moisture and holding edge portions of the absorbent walls tightly between said tongues and walls of said grooves, and means for supplying water to said absorbent walls. 50

3. In a refrigerator, the combination with an open framework and absorbent walls secured thereto, of means for discharging water against the absorbent walls, an external gutter at the bottom of the refrigerator to receive surplus water from said walls, and a deflector of water proof material located within the refrigerator at the lower ends of the absorbent walls and adapted to direct water through the latter to said external 60 gutter.

4. In a refrigerator, the combination with an open framework and absorbent material secured to said framework and composing the walls of the refrigerator, of a plurality 65 of superimposed pockets or troughs of absorbent material secured to said absorbent walls, and means for supplying water to said absorbent walls.

In testimony whereof I have signed this 70 specification in the presence of two subscribing witnesses.

WILLIAM WOODROW DOUGLASS.
